(57) **CLAIM**

The ornamental design for accessory for medical care apparatus, as shown and described.

DESCRIPTION

FIG. 1 is a top plan view of an open configuration of an accessory for medical care apparatus.

FIG. 2 is a bottom plan view of an open configuration of the accessory for medical care apparatus shown in FIG. 1.

FIG. 3 is a top front perspective view of an open configuration of the accessory for medical care apparatus shown in FIG. 1.

FIG. 4 is a bottom front perspective view of an open configuration of the accessory for medical care apparatus shown in FIG. 1.

FIG. 5 is a left side elevational view an open configuration of the accessory for medical care apparatus shown in FIG. 1.

FIG. 6 is a top front perspective view of a partially closed configuration of the accessory for medical care apparatus shown in FIG. 1.

FIG. 7 is a bottom front perspective view of a partially closed configuration of the accessory for medical care apparatus shown in FIG. 1.

FIG. 8 is a right side elevational view an open configuration of the accessory for medical care apparatus shown in FIG. 1.

FIG. 9 is a top plan view of an open configuration of a second embodiment of an accessory for medical care apparatus; the stippling shown in each of FIGS. 9-16 represents difference in materials.

FIG. 10 is a bottom plan view of an open configuration of the accessory for medical care apparatus shown in FIG. 9.

FIG. 11 is a top front perspective view of an open configuration of the accessory for medical care apparatus shown in FIG. 9.

FIG. 12 is a bottom front perspective view of an open configuration of the accessory for medical care apparatus shown in FIG. 9.

FIG. 13 is a left side elevational view an open configuration of the accessory for medical care apparatus shown in FIG. 9.

FIG. 14 is a top front perspective view of a partially closed configuration of the accessory for medical care apparatus shown in FIG. 9.

FIG. 15 is a bottom front perspective view of a partially closed configuration of the accessory for medical care apparatus shown in FIG. 9; and,

(Continued)

FIG. 16 is a right side elevational view an open configuration of the accessory for medical care apparatus shown in FIG. 9.
